UNITED STATES PATENT OFFICE.

CHARLES J. KINTNER, OF NEW YORK, N. Y.

ELECTRIC RAILWAY.

SPECIFICATION forming part of Letters Patent No. 700,127, dated May 13, 1902.

Original application filed May 6, 1901, Serial No. 58,923. Divided and this application filed March 20, 1902. Serial No. 99,141. (No model.)

To all whom it may concern:

Be it known that I, CHARLES J. KINTNER, a citizen of the United States, residing at New York, borough of Manhattan, county and 5 State of New York, have made a new and useful Invention in Electric Railways, of which the following is a specification.

My invention is directed particularly to improvements in electric railways of the sectional third-rail or conductor type, and has for its objects, first, to avoid damaging arcing at the terminals of the switches when the sectional third rails or conductors are disconnected from the current feeder or main; 15 second, to avoid damaging effects upon the translating devices, as motors, electric lamps, &c., carried by the cars when the current-collector or trolley passes from one sectional conductor to another.

Heretofore in systems of electric railways, so far as I am aware, it has not been possible to practically utilize normally dead sectional third rails or conductors where currents of enormous quantity and high potential difference are used, owing to the fact that when the sectional third rails or conductors are disconnected from the current feeder or main as a car passes over the route the terminals of the switches are fused or damaged to such 25 an extent as to make the system impracticable. With such systems also where the current is disconnected from and suddenly again connected to the motor and translating devices carried by a car more or less damage 30 results, often rupturing the lamps by the too-sudden supply of the entire working current thereto.

My invention contemplates the lowering of the current-flow through the terminals of 40 any switch of the system at the time that its corresponding sectional conductor is being disconnected from the current feeder or main to such an extent as to avoid any damaging arcing, and this I accomplish by the use of 45 the apparatus hereinafter described and illustrated in the accompanying drawings and by the practice of the methods hereinafter claimed.

For a full and clear understanding of the 50 invention, such as will enable others skilled in the art to use the apparatus described and

to practice the methods hereinafter claimed, reference is had to the accompanying drawings, in which—

Figure 1 is a diagrammatic view of a part 55 of a sectional-third-rail system of electric railways embodying the present invention, and such as is disclosed in a prior application filed by me in the United States Patent Office on the 6th day of May, 1901, bearing Serial No. 58,923, of which application the present is a division. Fig. 2 is a similar diagrammatic view of a modified form of apparatus for practicing the methods hereinafter claimed. Fig. 3 is a detail diagrammatic 65 view of a still further modified form of apparatus for practicing the methods hereinafter claimed.

Referring first to Fig. 1, *c* represents the current feeder or main, and *t* one of the tram- 70 rails of an electric-railway system, *r r* being adjoining sectional third rails or conductors electrically connected by short branch conductors *2 2* to yielding terminals *s s* in a switch-box, (not shown in this view of the 75 drawings, but indicated by the letters *sb* in Fig. 2.) *7 7* are releasing-conductors running in opposite directions and electrically connected, respectively, to the adjoining ends of the short branch conductors *2 2* at the ends 80 of the sectional conductors *r r*, the opposite ends of said conductors *7 7* being connected, respectively, to independent coils of a releasing-magnet *15* and then to the tram-rail or return-conductor *t*. *ff* are switch-operat- 85 ing magnets connected in short branch conductors *3 3*, having their opposite ends connected, respectively, to short working conductors *5 5* and to the tram-rail or return-conductor *t*. *r' r'' r'''* are short sectional rails 90 or conductors located in alinement with the sectional third rails or conductors *r r*, the conductor *r'* in each instance being connected to its corresponding third rail or conductor *r* by a resistance of, say, one hundred ohms, 95 and the two conductors *r' r''* being connected together in a similar manner by corresponding resistances of, say, two hundred ohms, the conductors *r'' r'''* being similarly connected by corresponding resistances of, say, three 100 hundred ohms, so that the total resistance in circuit from right to left and from left to right,

respectively, between the two third rails r r' and the adjoining ends of the short rails r^3 r^3 is, say, six hundred ohms, said short rails r' r^2 r^3 and resistances one hundred, two hundred, and three hundred ohms being in shunt relation to the branch conductors 2 2, running to the switching-terminals s s . The short working conductors 5 5 are located, respectively, on opposite sides of the adjoining short conductors r^3 r^3 and parallel therewith. 17 is a locking armature-lever electrically connected by a short branch conductor 1 with the current-feeder c . a is a hand-switch pivoted to the insulating-base of the switch and having an insulating-bar near its free end for enabling an authorized person to manually lock either of the yielding terminals into connection with the armature-lever 17. The arrangement of all of the parts so far described 20 is duplicated at each switch-box in the manner disclosed in the before-mentioned application, and further description is not deemed necessary here, the present invention having only to deal with the method of avoiding ab- 25 normal or damaging arcing between the terminals s s and lever 17, the present invention being applicable in connection with all sectional third-rail or conductor systems of electric railways, which are automatically connected to and disconnected from the current 30 feeder or main as a car passes by or over the route. m represents an electric motor on board a car, (not shown,) moving from left to right, and 16 one of the tram-wheels, 4 being the working conductor, operatively connecting the motor m with a current-collector or trolley 14 and with one of the tram-wheels. 18 are signal-lamps located in multiple-arc branch circuits between the releasing-con- 35 ductors 7 7 and the tram-rail or return-con- ductor t . The tram-rail t and all of the conductors carrying the working current to the motor m are illustrated in heavy black lines, while the releasing-conductors and the switch- 40 operating circuits are illustrated in light black lines. The car is supposed to be trav- 45 eling from left to right in the direction of the arrows with the current-collector or trolley 14 upon a live sectional conductor r . As this 50 current-collector or trolley passes upon the short sectional conductor r' on the left a re- 55 sistance of one hundred ohms is cut into circuit, and as it advances ultimately two hundred and three hundred ohms are suc- 60 cessively cut into circuit, so that if the voltage of the power-house generator is six hundred there will be flowing through the motor m , when the current-collector 14 passes upon the sectional conductor 4, one ampere of current. 65 As the current-collector advances the circuit is closed by the short working conductor 5, conductor 3 on the right, through the right-hand switch-magnet f , and the terminal s on the right is automatically locked in connec- 70 tion with the locking-terminal 17, so that the next sectional third rail r in advance is now made alive, circuit being from the current

feeder or main c by branch conductor 1, locking armature-lever 17, right-hand yielding terminal s , right-hand branch conductor 2. 70 Consequently circuit was closed by the releasing-conductor 7 to the rear, releasing the terminal s in the switch-box last passed; but inasmuch as there is now six hundred ohms resistance in the circuit there will be no dam- 75 aging current flowing through the terminal of the switch at that point. Hence the circuit is interrupted without arcing. As the current-collector 14 advances the resistances three hundred, two hundred, and one hun- 80 dred are successively cut out of circuit and the working current gradually restored to normal by the time that the collector 14 reaches the sectional third rail or conductor r , so that no damaging effect is felt by the 85 lamps, motors, or other translating devices carried by the car. Of course it will be understood that during the time the car is trav- 90 eling from the point where it is located in the drawings to a corresponding point on the extreme right there will be insufficient current flowing through the motor to move the same. Therefore it will be necessary that it should have sufficient momentum to carry it over this distance. When the car is running in a re- 95 verse direction, it is only necessary to reverse the trolley 14, so that it makes contact with the working conductor 5 on the other side of the rail r^3 , thereby closing the circuit through the operating-magnet f on the left, all as fully 100 disclosed in the before-mentioned application, and further description is not deemed necessary here, as this feature does not constitute any part of the present invention.

In Fig. 2 of the drawings I have illustrated 105 a modified form of the invention in which all of the circuit connections, in so far as the sys- 110 tem is concerned, are the same as shown in Fig. 1, except that in this case the resistances in the roadway—one hundred, two hundred, 115 and three hundred—are done away with and the conductors 2 2 connected directly to the ends of the adjoining sectional third rails and to the terminals s s in the switch-boxes. How- 120 ever, in this form of the apparatus for prac- 125 ticing the methods hereinafter claimed the means for varying the current-flow through the terminals is carried on board of the car and consists of a rheostat r_h , embracing suc- 130 cessive resistances running, as shown, from 120 seventy-five to six hundred ohms, y being a contact-arm carried by a conducting-lever l , pivotally supported and connected to an arm u , extending downward to a point beneath the car, the lower end of said arm having a 135 trolley q , adapted to move over either end of a third rail n' in the road-bed, which is inclined for a definite distance in opposite directions, as shown, v being a strong spiral spring for holding the lever l , the arm u , and trolley q 140 in its lower position. dp is a dash-dot connected to the lever l for gradually regulating the movements of said lever under the influ- 145 ence of the spring v . h is an operating-han-

idle carried by the lever *l* and insulated therefrom for enabling a motorman to move said lever at his pleasure. 20 represents the controller on board the car; *m*, the motor; 16, one of the tram-car wheels, as before, and 4 the working conductor for conveying the current from the current-collector 14 to and through the motor to the tram-rail or return-conductor *t*. The operation of this modified 5 form is as follows: Suppose a car to be moving from left to right in the direction of the arrow and that the current flowing through the motor *m* at the time is a maximum, with the lever *l* in the position shown in dotted 10 lines. As the car passes over the inclined rail *n'* the trolley *q*, acting against the spring *v*, causes the lever *l* to be lifted, so that the contact-arm *y* gradually rises and throws successive sections of the rheostat *rh* into circuit until at the time when the current-collector 14 passes from one sectional third rail *r* to the other the maximum amount of resistance is thrown into circuit, as shown in full 15 lines, so that, as in the first instance, there is now a minimum amount of current flowing through the terminals in the switch-box at the end of the next section in the rear. Consequently when the terminal is released at the distant end of the section last passed there 20 will be no damaging arcing at that point. Instead of providing a separate or independent double-inclined rail *n'* in the roadway I may incline the adjoining ends of the sectional third rails *r*, and the arm *u* and trolley *q* may 25 in this instance be the conducting-trolley which conveys the current directly to the lever *l*, such change being an obvious one to those skilled in the art. Such a modification is shown in Fig. 3, in which the tram-rails *r r* are 30 inclined upward toward each other at their adjoining ends and the circuit connections are made therefrom directly through the trolley 14 and the operating-arms *u* and *l* to the rheostat and motor, as before.

45 Although I have hereinbefore described and have illustrated in the accompanying drawings two modified forms of apparatus for practicing the methods hereinafter claimed, I do not limit my invention to these specific 50 types of apparatus, as I believe it is broadly new with me to accomplish the result sought—namely, to prevent abnormal or damaging arcing at the terminals of the switches in a sectional-third-rail system when the sectional 55 third rails or conductors are disconnected from the current feeder or main by reducing the current-flow at that time through the terminals to an amount insufficient to damage the same.

60 I am aware that it has heretofore been proposed to insert resistances at the ends of each of a series of sectional third rails or conductors for the purpose of avoiding flashing or abnormal arcing at these points, as dis- 65 closed in British patent to Smith, No. 11,963, of August 18, 1888, and that short sectional

working conductors, located in alinement with other working conductors and provided with resistances for reducing the current-flow as a current-collector passes thereover, have 70 been utilized, for the purpose of avoiding damaging arcing at the ends of adjoining working conductors, as disclosed in United States patent to Heilmann, No. 622,466, granted April 4, 1899; but I am not aware that 75 any one has heretofore devised means whereby abnormal or damaging arcing may be avoided between the terminals of the switches of a sectional-third-rail system of electric railways by reducing the current-flow through 80 the terminals at the time that the circuit is interrupted at such points, and this constitutes the essence of the present invention, in that it makes it possible to utilize currents of very large quantity and high-potential difference in connection with sectional conductor or third-rail systems of electric railways and without danger of fusing or destroying the switching-terminals, this objectionable feature having made it necessary here- 85 tofore to use carbon at the switching-terminals, which carbon terminals had to be replaced after a time owing to the damaging arcing.

With my invention and in the practice of my 90 methods it is possible to use metallic terminals of sufficient current-carrying capacity to deliver current in enormous quantities and of widely-varying potential differences, owing to the fact, as will be appreciated, that when 95 the circuit is interrupted at the terminals insufficient current is flowing to in any sense damage such terminals.

No claim is made in the present application to the novel safety system of electric railways illustrated in the accompanying drawings, whereby front and rear end collisions are avoided, nor to the method of avoiding either front or rear end collisions by the use of such a system, as these features are respectively claimed in the before-mentioned application, bearing Serial No. 58,923, filed May 6, 1901, of which the present application is a division, and another application, bearing Serial No. 84,322, filed December 2, 1901, 115 which is also a division of the before-mentioned application, Serial No. 58,923.

Having thus described my invention, what I claim, and desire to secure by Letters Patent of the United States, is—

1. In a system of electric railways of the sectional-conductor type the method of preventing abnormal or damaging arcing at the terminals of the switches where the sectional conductors are connected to and disconnected 120 from the current feeder or main; consisting in automatically reducing the current-flow delivered through the terminals by successive steps until a current is flowing to an amount insufficient to damage the same at the time 125 that the sectional conductor is disconnected from the feeder or main.

2. In a system of electric railways of the sectional-conductor type the method of preventing abnormal or damaging arcing at the terminals of the switches where the sectional conductors are connected to and disconnected from the current feeder or main; consisting in automatically increasing the resistance to the current delivered through the terminals by successive steps until a current is flowing to an amount insufficient to damage the same at the time that the sectional conductor is disconnected from the feeder or main.
3. In a system of electric railways of the sectional-conductor type the method of preventing abnormal or damaging arcing at the terminals of the switches where the sectional conductors are connected to and disconnected from the current feeder or main, and damage to the current-collector and translating devices carried by a car; consisting in automatically reducing the current-flow through the terminals and to the translating devices as the current-collector passes from one sectional conductor to another and correspondingly increasing the current-flow as it ad-

vances upon the next adjacent sectional conductor.

4. In a system of electric railways of the sectional-conductor type the method of preventing abnormal or damaging arcing at the terminals of the switches where the sectional conductors are connected to and disconnected from the current feeder or main, and damage to the current-collector and translating devices carried by a car; consisting in automatically increasing the resistance to the current delivered through the terminals and at the ends of adjacent sectional conductors as the current-collector passes from one sectional conductor to another, and in correspondingly decreasing the resistance to the current-flow as it advances upon the next adjacent sectional conductor.

In testimony whereof I have signed my name to this specification in the presence of two subscribing witnesses.

CHARLES J. KINTNER.
